CLAIM

The ornamental design for a hydraulic jack as shown and described.

DESCRIPTION

FIG. 1 is a front elevation view of a hydraulic jack showing our new design;

FIG. 2 is a rear elevation view thereof;

FIG. 3 is a left side elevation view thereof;

FIG. 4 is a right side elevation view thereof;

FIG. 5 is a bottom plan view thereof;

FIG. 6 is a top plan view thereof;

FIG. 7 is a front, top, left side perspective view thereof;

FIG. 8 is a front, top, right side perspective view thereof; and,

FIG. 9 is a rear, top, right side perspective view thereof.

The broken lines in the drawings show portions of the hydraulic jack that form no part of the claimed design.
